DESIGN FOR A TOOL FOR INSTALLING CONDUIT CLIPS

Eugene M. Morehouse, Tujunga, Calif., assignor
to Adel Precision Products Corp., a corporation
of California

Application July 20, 1943, Serial No. 110,713

Term of patent 14 years

To all whom it may concern:

Be it known that I, Eugene M. Morehouse, a citizen of the United States and residing at Tujunga, in the county of Los Angeles, State of California, have invented a new, original, and ornamental Design for Tool for Installing Conduit Clips, of which the following is a specification, reference being had to the accompanying drawing, forming part thereof, in which:

Fig. 1 is a top plan view of a tool for installing conduit clips showing my new design;

Fig. 2 is a side elevation of the tool thereof;
Fig. 3 is a bottom plan view of the tool thereof;
Fig. 4 is an end elevation of the tool thereof
looking toward the left end as shown in Fig. 1;
Fig. 5 is an end elevation of the tool thereof
looking toward the right end as shown in Fig. 1.

I claim:

The ornamental design for a tool for installing conduit clips, as shown.

EUGENE M. MOREHOUSE.
